UNITED STATES PATENT OFFICE.

CHARLES C. CLUTCH, OF YORKLYN, DELAWARE.

PAPER-MAKING MACHINE.

Application filed March 2, 1922. Serial No. 540,407.

To all whom it may concern:

Be it known that I, CHARLES C. CLUTCH, a citizen of the United States, residing at Yorklyn, in the county of New Castle and 5 State of Delaware, have invented new and useful Improvements in a Paper-Making Machine, of which the following is a specification.

My invention relates to new and useful 10 improvements in a paper making machine and more particularly with relation to the apron board thereof, the object of which is to provide a simple and effective means for regulating the flow of paper stock according 15 to the different natures and weights thereof.

Another object of the invention is to provide for adjusting the apron board vertically and also horizontally relative to a slice bar so that the apron may be moved into close 20 proximity to said slice bar when running free stock and may be moved therefrom when running slow stock.

Another object of the invention is to provide an adjustable apron board whereby it 25 may be quickly and conveniently adjusted transversely of the machine to control the size of the paper sheet without the necessity of detaching any portion of the apron board.

A further object of the invention is to 30 so construct and arrange the apron parts or sections that they will not curl along their edges or at their corners when being adjusted.

With these ends in view, this invention 35 consists in the details of construction and combination of elements hereinafter set forth and then specifically designated by the claims.

In order that those skilled in the art to 40 which this invention appertains, may understand how to make and use the same, I will describe its construction in detail, referring by numerals to the accompanying drawings forming a part of this application, 45 in which:—

Fig. 1, is a fragmentary perspective view of a paper making machine in the region of the apron board.

Fig. 2, is an end view of the apron board 50 detached from the machine.

Fig. 3, is a front elevation thereof.

Fig. 4, is a plan view of the same.

In carrying out my invention as here embodied, 2 represents a paper making machine 55 provided with the Fourdrinier wire 3 running over rollers, one of which is shown at 4,

To suitable parts of the frame of the machine at each side of the Fourdrinier wire is secured a bracket 5 consisting of an upright 6 having a vertical longitudinal slot 7 therein for the passage of a suitable attaching means 8, such as a bolt which is screwed into the machine frame and by which the bracket is held in any desired vertical adjustment, as will be obvious. Projecting from the upper end of the upright 6 is an arm 9 having a longitudinal slot 10 therein for the passage of suitable fastening means 11, such as a bolt or screw which has threaded connection with the apron support 12, said fastening means 11 preventing the accidental displacement of the support 12 permitting a longitudinal movement of the latter relative to the arm 9 of the bracket. The arm 9 is also provided with a pair of 70 spaced lugs 13 and 14 one on each side of the slot 10 and threaded through these lugs are the adjusting screws 15 and 16 which engage the back and front respectively of the support 12 so that as one is backed out and the other screwed inwardly the support 12 will be moved in the desired direction.

The support 12 is provided with a longitudinal groove 17 preferably arcuate in cross section and in which are mounted the bars 18, each of which has secured thereto the inner or rear member 19 of the shields 20, the outer or forward members 21 projecting forwardly beyond the front edge of the support 12 at right angles to the inner members 19.

The apron 22 is made in three sections 23, 24 and 25, the wings 23 and 24 being made to overlap the center or stationary section 25. The stationary section 25 is fastened along its rear edge to the support 12 by 95 suitable fastening devices 26 while the wing sections 23 and 24 are secured to one of the forwardly projecting members 21 of the shields 20 and to one of the sliding bars 18 in any suitable and well known manner, such as by a strip 27 and the fastening devices 28. The adjacent edges of the wing sections 23 and 24 are cut on an angle as at 29 so that their inner edges diverge from their 100 rear edges toward their forward edges and it has been found in actual practice that such construction permits the apron to be adjusted without the possibility of any of the sections curling since the central section is never moved and the weight of the paper stock rests upon the edges of the wing sections.

Fig. 1, is a fragmentary perspective view of a paper making machine in the region of the apron board.

Fig. 2, is an end view of the apron board 50 detached from the machine.

Fig. 3, is a front elevation thereof.

Fig. 4, is a plan view of the same.

In carrying out my invention as here embodied, 2 represents a paper making machine 55 provided with the Fourdrinier wire 3 running over rollers, one of which is shown at 4,

From the foregoing it will be evident that an apron constructed in this manner may be readily and quickly adjusted for different width papers without having to remove 5 any of the parts without the possibility of any of said parts becoming loosened or accidentally displaced and since the inner edges or the corners of the adjustable sections will not curl the life of the apron is 10 greatly prolonged making a large saving in both time and money.

It being possible to adjust the apron board both vertically and horizontally through the medium of the brackets 5 relative to the slice bar 30 without having to stop the machine it is possible to regulate the flow of paper stock advantageously as it is the paper maker's desire to have the outer edge of the apron in close proximity 15 to the slice bar when free stock is being run too quickly and to have the inner end of said apron a greater distance from the slice bar when a slow stock is being run to permit the surplus water to flow from the paper 20 stock prior to passing beneath the slice bar.

Of course I do not wish to be limited to the exact details of construction as herein shown as these may be varied within the limits of the appended claims without departing 30 from the spirit of my invention.

Having thus fully described my invention, what I claim as new and useful is:—

1. A paper making machine comprising in combination, a slice bar, vertically adjustable brackets for supporting an apron, said apron and means to adjust the apron 35 horizontally relative to said slice bar.

2. In a paper making machine, a slice bar, an apron and means to adjust said apron vertically and horizontally relative to said slice bar.

3. A paper making machine including an apron, brackets to support said apron, means to adjust said apron horizontally on 45 the supporting brackets, and means to adjust the brackets vertically.

4. A paper making machine comprising in combination, the machine, brackets secured to said machine, each of said brackets 50 consisting of an upright having a longitudinal slot for the passage of a suitable fastening means, an arm having a longitudinal slot, a pair of spaced lugs formed on the arm, one beyond each end of the last named slot, 55 and an adjusting screw threaded through each of said lugs, an apron support mounted on said brackets and adjustable horizontally by means of the adjusting screws and fastening means passing through the slots 60 in the bracket arms and attached to the apron support to prevent accidental displacement of the apron support.

5. In a device of the character stated, a central stationary section and two adjustable wing sections overlapping and resting 65 upon the central stationary section.

6. In a device of the character stated, a central stationary section and two adjustable wing sections overlapping and resting 70 upon the ends of the central stationary section, the adjacent edges of said wing sections being formed on an angle so that the said edges diverge from the inner toward the outer edges of said wing sections.

7. In a device of the character stated, an 75 apron board, a central stationary apron section supported by said board and projecting from the front edge thereof, and two wing sections connected with said board overlapping and resting upon the ends of 80 the central stationary section.

8. In a device of the character stated, an apron board, a central stationary apron section supported by said board and projecting from the front edge thereof, and two wing sections connected with said board 85 overlapping and resting upon the ends of the central stationary section, the adjacent edges of said wing sections diverging from their inner edges toward their outer edges. 90

9. In a device of the character stated, an apron board having a longitudinal arcuate groove thereon, independently sliding bars mounted in said groove, shields each comprising two members lying at right angles 95 to one another, one of said members being secured to each of the sliding bars, a central stationary apron section supported by said apron board and projecting forwardly therefrom, and wing sections overlapping the central section resting thereon and having certain of their edges secured to the 100 sliding bars and the other members of the shields.

10. In a device of the character stated, an apron board having a longitudinal arcuate groove therein, independently sliding bars mounted in said groove, shields each comprising two members lying at right angles to one another, one of said members being secured to each of the sliding bars, a central stationary apron section supported by 110 said apron board and projecting forwardly therefrom, and wing sections overlapping the central section resting thereon and having certain of their edges secured to the sliding bars and the other members of the shields, the adjacent edges of said wing sections diverging from their inner edges toward 115 their outer edges. 120

In testimony whereof, I have hereunto affixed my signature.

CHARLES C. CLUTCH.
